UNITED STATES PATENT OFFICE.

HAROLD CUSACK, OF CHICAGO, ILLINOIS, ASSIGNOR TO THOS. CUSACK COMPANY, OF CHICAGO, ILLINOIS, A CORPORATION OF NEW JERSEY.

DESIGN FOR A SIGN.

47,242.

Specification for Design.

Patented Apr. 20, 1915.

Application filed January 20, 1915. Serial No. 3,421. Term of patent 3½ years.

To all whom it may concern:

Be it known that I, HAROLD CUSACK, a citizen of the United States, and a resident of the city of Chicago, county of Cook, and State of Illinois, have invented a new, original, and ornamental Design for Signs, of which the following is a specification, reference being had to the accompanying drawing, forming part thereof.

In the accompanying drawings Figure 1

represents a view in front elevation of my novel sign design and Fig. 2 represents an end view thereof.

I claim:

The ornamental design for a sign, as shown.

HAROLD CUSACK.
